UNITED STATES PATENT OFFICE.

GEORGE WOOD, OF SEATTLE, WASHINGTON, ASSIGNOR TO ALEC. J. GERRARD, OF CHICAGO, ILLINOIS.

BOX-STRAPPING BENCH.

Application filed January 22, 1920. Serial No. 353,311.

To all whom it may concern:

Be it known that I, GEORGE Wood, a citizen of the United States of America, and resident of the city of Seattle, county of 5 King, and State of Washington, have invented certain new and useful Improvements in Box-Strapping Benches, of which the following is a specification.

My invention relates to a bench or table 10 intended for handling a box while putting a strap or hoop about the same.

The object of my invention is to provide a table which will enable the box to be more conveniently and rapidly handled while 15 placing reinforcing hoops or wires about the same, than would be possible by placing it upon an ordinary table or support.

My invention consists of the use of a turn 20 table support for the box together with means for conveniently handling and controlling the same and also in the provision of means for supporting the wire tying tool when the same is not in use. It also consists of means whereby the above mechanisms are adjustable to fit different 25 conditions.

The features of this invention which I believe to be new and upon which I desire to 30 secure a patent will be hereinafter described and then particularly pointed out by the claims terminating this specification.

In the accompanying drawings I have 35 shown my device constructed in accordance with my present preferred forms.

Figure 1 is an elevation of the device as 40 seen from the side at which the workman stands.

Figure 2 is an elevation of the same device 45 seen at a different view point and with the standard in section.

Figure 3 is a side view showing a modification, designed for being placed upon an ordinary bench.

It is customary to prepare boxes and packages, and particularly if they are designed 45 for shipment to any great distance, by placing about them reinforcing hoops or bands. My invention is designed to form a bench or table for the reception of such boxes or packages so as to facilitate doing this work. In the form of the device as shown in Figures 1 and 2, it is shown as carried by a post or pillar which is secured to the floor, while in Figure 3 it is shown as provided with

a low base and is intended to be supported from a bench or any other raised surface. The device as shown in Figures 1 and 2 employs a tubular post 1 which is provided with a base, as 10, adapted to be secured to the floor. A second tube 2 is adapted to telescope within the base tube 1 and in this way means are provided whereby the working height of the turntable may be varied. This may be done by providing the inner tube 2 with a series of holes 20 which are adapted to receive a pin 21 which also passes through the upper end of the base section 1 of the pillar.

Mounted upon the upper end of the central tube 2 is a collar 3. This is adapted to turn upon the tube 2. This collar 3 carries the turn-table 4. The turn-table may be of any suitable construction and size. As illustrated it is provided with low upturned flanges 40 upon two sides and with other flanges 41 at the other two sides, which latter flanges are turned downward. The flanges 41 serve to materially stiffen the table while the flanges 40 serve to secure the box or package in secure position and in addition give a certain measure of stiffness to the table.

The lower end of the collar 3 may be provided with two notches 30 placed at diametrically opposed positions. These slots are adapted to receive a locking catch 31 which is mounted to reciprocate within a guide 32 and is normally held up, or in locking position, by a spring 33. Secured to the catch 31 is a rod 34 which is operatively connected with a treadle lever 35. The rod 34 may be made to telescope with a tube 36 so that the length of the connection between the lever and the catch may be varied. A clamping bolt 37 may be employed to secure these two parts in adjusted relation.

The tool employed for securing the wire hoops about a box is of some little weight. It is employed by placing it upon the box during the time of securing the hoop. As it must be removed when the box is shifted in position and also when removing the box and replacing it with another, I have provided an elevated support therefor, the same consisting of a shelf 51 which is carried by an arm 50. This arm is bent in its lower portion so as to be secured to the upper member 2 of the pillar. This is shown as

being done by forming a band 52 which is bolted to the pillar. The upwardly rising portion of this arm, at the level occupied by the box when the hoop is being placed thereon, should be placed to one side of the outer edge of the turn-table a sufficient distance to permit free swinging of the box when it is upon the turn-table. The arm 50 may be reinforced by a compound telescopic brace, as 10 5, or in any other suitable manner.

In Figure 3 is shown the manner of constructing this device when it is designed for placing upon a bench. The pillar construction is omitted, otherwise, it is essentially 15 the same as that shown in Figures 1 and 2. As shown in Figure 3 no provision has been made for stopping the turn-table in an exact position. While such a mechanism, the same as shown in Figure 1, consisting of the 20 catch 31 and the notches, 30, might be desirable, I do not consider that it is essential. If the turntable be easily moved the operator will soon become expert in turning it to the proper position. In using my device the 25 box is placed upon the turn-table with its ends over-hanging the same. The length of the box and the length of the turn-table should be such as to give enough over-hang of the box at each end to permit placing of the 30 wire hoop at the points desired. The wire tying tool may be placed upon the shelf 51. This shelf should preferably be a very slight distance above, or about at the level of the upper surface of the box and a little to one 35 side of the side margin thereof. The position as best shown in Figures 1 and 3 is desirable.

To place the hoop about the box, the wire tying tool is placed upon the box and by its 40 use the hoop is secured upon the box. The tool is then lifted back to the shelf 51, the turn-table with the box thereon turned half way around, which brings the opposite end

of the box in position for receiving its reinforcing hoop. 45

The upwardly extending portion of the arm which supports the shelf 51, may be made adjustable so as to be able to adjust the level of the shelf to correspond with boxes of different sizes. In Figure 3 I have shown one manner of doing this, the same consisting in making the supporting arm in two parts, 53 and 54, and providing one or both of these with a series of holes through two of which the securing bolt 55 may be passed and through the other a pin 56, which is adapted to enter other holes; or, in lieu of the pin 56, a second bolt may be employed. 50 55

What I claim as my invention is:

1. A box strapping bench comprising a 60 base, a box holding table carried by the base and vertically adjustable, an arm secured to the base and extending outwardly and upwardly at a distance from the center to clear the box being operated upon, a shelf carried by the upper end of said arm well above the box holding table and laterally removed therefrom, and an adjustable brace connected with the outer parts of said arm and adapted to reach the floor. 65 70

2. A box strapping bench comprising a base, a vertically adjustable base extension, a box holding table carried upon said extension, an arm secured to the said extension and extending outwardly and upwardly at a 75 distance from the center to clear the box being operated upon, a shelf carried by the upper end of said arm just above and at one side of the said table, and a brace consisting of telescopic members hinged to the outer part of said arm and adapted to engage the floor. 80

Signed at Seattle, King County, Washington this 15th day of January, 1920.

GEORGE WOOD.
